UNITED STATES PATENT OFFICE.

WILLIAM HACKLY CHURCH, OF SUPERB, SASKATCHEWAN, CANADA.

ATTACHMENT TO SHOCKING-MACHINES.

1,341,167.

Specification of Letters Patent. Patented May 25, 1920.

Application filed April 16, 1918. Serial No. 228,842.

To all whom it may concern:

Be it known that I, WILLIAM HACKLY CHURCH, of the town of Superb, in the Province of Saskatchewan, Canada, have invented certain new and useful Improvements in Attachments to Shocking-Machines, of which the following is the specification.

The invention relates to improvements in attachments to shocking machines, and particularly to an improvement in my previous grain shocker, which is fully disclosed and described in U. S. Patent 1,240,823 dated the 25th day of September, 1917, and the objects of the invention are to provide an improved form of elevator for taking the sheaves from the binder deck and elevating them to depositing position to the basket; to provide a means associated with the elevator for receiving the sheaves from the elevator and automatically discharging them into the basket and for storing the sheaves during the interval that the basket is dumping, and to provide a means for counting the sheaves as they pass to the elevator.

With the above general and other minor objects in view which will become more apparent as the description proceeds, the invention consists essentially in the arrangement and construction of parts hereinafter more particularly described and later pointed out in the appended claims, reference being had to the accompanying drawings in which:—

Figure 1 represents a plan view of my complete invention.

Fig. 2 represents an end view of the shocking machine with my invention applied.

Fig. 3 represents an enlarged detailed perspective view of the inner side of the shocker frame and parts carried thereby.

Fig. 4 represents a perspective view of one end of one of the trap doors.

Fig. 5 represents an enlarged detailed side view of part of the counting mechanism.

Fig. 6 represents a plan view of the parts appearing in Fig. 5.

Fig. 7 represents an enlarged detailed face view of the indicator.

Fig. 8 represents an interior view of the indicator, the end piece having been removed.

Fig. 9 is an enlarged detailed side view of the driving side of the elevator.

Fig. 10 is an enlarged sectional view through the elevator.

In the drawings like characters of reference indicate corresponding parts in each figure.

The shocking machine as herein disclosed is for the greater part constructed identically to the machine described in the patent hereinbefore referred to, and for this reason I have considered it unnecessary to give a detailed showing or description of the shocker except only in respect to those parts immediately associated with the present improvements.

The shocker frame indicated by the reference numeral 1, is carried at the outer side by a driving ground wheel 2, rotatably mounted on the basket shaft 3 which is provided intermediate of its end with a curvilinear portion 4 which carries a sheaf receiving and shock forming basket collector 5.

The ground wheel, as already stated, is rotatably mounted on the basket shaft but it is designed to drive the basket shaft upon the throwing in of an angular lever 6 carried by a crank member 7 secured to the shaft, the lever being designed to engage with the spokes of the wheel 2 so as to carry the shaft around with the wheel. The lever is arranged so that it can be manipulated in the same manner as disclosed in my prior patent, such being by way of a cable 8 which controls the action of a bell crank 9 mounted on the frame and engaging with the lever.

A frame 10 is carried by the shocker frame and co-acts with the lever 6 to control the same and is arranged so that after the wheel with the axle has made one complete revolution the lever 6 will be automatically disengaged and the wheel freed from the shaft. This latter frame 10 is identical to that described in the former patent and referred to and fully described therein.

The inner side of the basket frame is pivotally connected to the binder frame 11, such connection embodying front and rear bars 12 and 13 permanently secured to the inner member 1' of the basket frame and having their inner ends pivotally fastened by means of adjusting bolts 14 and 15 to brackets 14' and 15' permanently fastened to the binder frame. The brackets are each provided with a series of adjusting openings

to allow of adjusting the bolts and permitting of the raising or the lowering of the inner ends of the bars. This provision is made to accommodate any adjustment made 5 in the binder as occurs from time to time, dependent on the nature of the crop harvested.

Between the binder deck 16 and the basket collector, I mount an elevator 17 for receiving the sheaves ejected from the deck and carrying them up or elevating them to depositing position over the basket, which, it will be noticed, has an open top, and between the upper end of the elevator and the 10 basket I locate a hopper 18 which receives the sheaves thrown down by the elevator and controls their entering the basket. The elevator and hopper are now described in detail.

15 19 represents a substantially U-shaped supporting bar having the legs 19' and 19" thereof permanently secured one to the front beam of the shocker frame and the other to an archèd truss bar 20 extending between the rear ends of the beams forming the shocker frame. The bar 19 is disposed directly above the longitudinal axis of the basket and it carries the hopper 18 which is preferably formed from sheet metal and 20 presents an open top and bottom and has the side wall 18' thereof, toward the binder, inclined, as best shown in Fig. 2 of the drawings, to direct the sheaves toward the center of the basket collector. The hopper 25 is fitted with a pair of trap doors 21 and 22, the trap door 21 being pivotally secured at 21' to the outer side of the hopper while the trap door 22 is supplied at opposite ends 30 with lever extensions 23 pivotally secured to the hopper at 23' and having their extending ends connected in each instance by means of a link 24 to a lug 24' located on the trap door 21. The trap door 22 is further supplied with a pair of lever extensions 35 40 to the hopper at 23' and having their extending ends connected in each instance by means of a link 24 to a lug 24' located on the trap door 21. The trap door 22 is further supplied with a pair of lever extensions 45 50 which project toward the binder and are connected with parts later disclosed.

From the above arrangement it will be obvious that upon the levers 25 being thrown down the trap door 22 will close and in 55 closing will draw up the trap door 21 through the action of the lever extensions 23 and links 24. These trap doors, when open, allow the sheaves to escape from the hopper to the basket and also provide a means for guiding the sheaves to the basket from the hopper. When closed they will 60 obviously stop the sheaves and allow them to collect in the hopper, and at this time I might state that they are closed by parts later described during the interval that the basket is dumping.

The elevator 17 is now described in detail.

The bars 12 and 13 carry a platform 65 26 on which I mount a pair of standards 27

and 27' which are slotted lengthwise as indicated at 28. The lower end of the elevator is adjustably secured to the standards and has the upper end thereof connected to the hopper and it presents an under conveyer 29 and a top or floating conveyer 30.

The under conveyer is constructed as is usual from side frames 31 and 31' connected by a cross deck 31", and at the opposite ends of the deck I locate conveyer shafts 32 and 32' which are fitted with pairs of chain wheels carrying endless chains 33, the chains being fitted at suitable intervals with cross slats 34. Here it will be noticed that the ascending sides of the chains drag over the top side of the deck 31" while the descending sides of the chains are under the deck. The lower end of the lower conveyer is disposed at an obtuse angle to the body part thereof and is arranged such that the sheaves ejected from the binder deck 16 will be deposited directly onto the ascending side of the said conveyer at such lower end.

Owing to the bend or turn at the lower end of the under conveyer, it is necessary to supply idler wheels to carry the chains. These are indicated but are not described more fully as they serve the ordinary function.

The conveyer shaft 32' is connected to the upper inner corners of the hopper by means of a pair of swinging links 35 and 35' and the lower end of the conveyer is adjustably mounted in the standards by means of adjusting bolts 36, the bolts when loosened being free to travel in the slots to effect the required adjustment.

The upper or floating conveyer comprises the usual sides 37 and 37' and the connecting deck 37", and it is here to be noticed that the sides of the floating conveyer pass to the outer sides of the under conveyer and that the deck is on top, so to speak.

The floating conveyer is swung by upper and lower pairs of links 38 and 39 from the sides of the lower conveyer, the links allowing the floating conveyer to swing away from or close into the under conveyer according to the feed. The links 38 are fitted with extensions 38' and springs 40 are interposed between the upper ends of the extensions and the body of the lower conveyer, which act to normally hold the floating conveyer in against the under conveyer.

The floating conveyer presents end shafts 41 and 42 carrying rollers fitted with a continuous belt 43, the top side of the belt passing outside the deck 37" and the edges of the belt being contained normally within the sides of the lower conveyer. The conveyers are both driven by the wheel 2 which, when the machine is in use, is turning continuously. The said wheel is provided with a chain wheel 44 which carries a chain 45 operating a chain wheel 46 located on the outer 130

end of a driving shaft 46' suitably mounted on the front end of the shocker frame. The inner end of the shaft 46' is supplied with a beveled pinion 47 which meshes continuously with a beveled pinion 47' located at the forward end of the counter shaft 48 suitably mounted in bearings extending from the inner side of the beam 1' of the shocker frame.

49 represents a chain wheel secured to the shaft 48 and connected by means of a chain 49' with a driving chain wheel 50 secured to the end of the conveyer shaft 32' and providing a drive for the under conveyer 29. The shaft 42 of the floating conveyer is driven by a series of chain wheels, chains and gears directly from the shaft 32', the chains, chain wheels and gears being arranged so as not to interfere with the swinging movement of the floating conveyer and so as to effect the driving, in an upward direction, of the inner side of the floating conveyer.

From the above disclosure it will be apparent that the elevator is continuously driven and that as the sheaves are ejected from the deck they will be carried directly up between the opposing ascending sides of the floating and under conveyers and will be delivered from these conveyers directly into the hopper. Further it will be apparent, that the floating conveyer can accommodate itself to a heavy or light feed as required, depending on the nature of the crop, this by reason of the links and springs.

35 The trap doors of the hopper are controlled by parts now described so that they are closed when the basket is dumping and opened automatically when the basket returns to initial position. To accomplish this I provide two upstanding rocker arms 51 and 52 pivotally mounted on the shaft 48 and having their upper ends adjustably connected as indicated at 53 to levers 54 attached pivotally to the rear ends of the ex-

45 tensions 25.

On the underside of the inner beam 1' of the shocker frame I mount pivotally a short shaft 55 provided with a striker 56 extending inwardly toward the basket and with a 50 downwardly extending lever arm 57 which has the lower end connected by a link 58 to a rod 59 carried by the lower extremities of the rocker arms 51 and 52, it being here noted that the rod 59 is in a location considerably below the shaft 48.

The inner end of the basket shaft is fitted with a sleeve 60 carrying a controlling flange 60' having a flat side 60" and the rocker arms carry a cross bar 61 which is positioned above the shaft 48 and is arranged to work in conjunction with the flange. In the open position of the gates and the normal sheaf receiving position of the basket, the bar 61 is adapted to lie on the flat side

of the flange, which position is best shown in Fig. 3 of the drawings. Naturally the gates maintain an open position, under the action of gravity, and they keep the bar 61 on the flat side of the flange unless otherwise disturbed.

Upon the attendant dumping the basket, however, the striking plate 62 carried by the basket engages the striker 56 and by doing so causes the lower ends of both the rocker arms to be swung toward the binder 75 and the upper ends to be swung in the opposite direction sufficiently far to effect the closing of the gates through the action of the levers 54, extensions 25 and links 24. Coincident with this movement the cross bar 80 61 is swung inwardly over the sleeve and clear of the flange, and in the continued turning movement of the basket becomes automatically locked behind the flange so that it is impossible for the gates, which are then 85 closed, to open. The gates consequently remain closed and locked closed until the basket completes its revolution to bring the flat side of the flange back to the original position. Immediately this occurs the 90 weight of the gates and sheaves within the hopper operate to throw down the gates and return the parts associated therewith to the original position, which is with the bar 61 directly above the flat side of the flange. 95

From the above it will be apparent that during the whole interval that the basket is dumping the sheaves which are being elevated by the elevator are being caught and retained in the hopper and that as soon as 100 the basket returns to its initial sheaf receiving position the gates are automatically released by the basket and the sheaves are freed to pass into the basket.

It is desirable in shocking machines for 105 the attendant to know just how many sheaves are in his basket at the time he wishes to dump it, and for this purpose I provide on my machine an indicator which is actuated by the sheaves passing to the elevator and 110 is reset by the basket when the basket dumps. The indicator is best shown in Figs. 7 and 8 of the drawings, and comprises a casing 63 in which I mount a short shaft 64 carrying a hand, pointer or indicator 65, the hand operating over a scale 66 having spaced and numbered marks thereon to indicate the number of sheaves. In the drawings the hand is set as pointing to the zero mark. However, upon it being thrown to the left it 115 120 will point at one or other of the divisions and if it goes six divisions, will indicate six sheaves, this number being directly opposite the sixth divisional mark.

A stop pin 67 limits the movement of the 125 hand in the right hand direction and prevents it from turning in that direction past the zero mark, and the hand is normally

constantly turned toward the zero mark by the action of a coiled spring 68 passing around the shaft and having one end secured to the inner side of the casing and the other end made fast to a pulley 69 permanently secured to the shaft.

On the pulley I wind a cable, cord or such like 70 which has one end made fast to the pulley and the other end projected over a pulley 71 and extending from the indicator to a counting mechanism 72 located on the side of the elevator. The cable is wound on the pulley so that when it is drawn off it acts to wind up the spring, with the result that when the cable is wound and released the spring immediately throws the hand back to the stop pin and resets it at zero. The indicator is preferably secured to the rear end of the inner beam 1' of the shocker frame so that it can be readily seen by the attendant on the binder at all times.

The counting mechanism comprises a drum 73 located on a short spindle 74 and formed integral with a ratchet wheel 75, the teeth of the ratchet wheel being controlled by the action of a pair of specially designed spring pressed pawls 76 and 77. The cable 70 is fastened to the drum, the arrangement being such that when the ratchet wheel is turned in the direction indicated by the applied arrow, (see Fig. 5) the cable will be wound on the drum 73 and will operate to pull in a direction to swing the pointer to the left, (see Fig. 7).

The pawl 76 is pivotally carried by a bail bar 78 spanning the drum and ratchet wheel and mounted on the shaft 74 and the bail bar is connected by means of an actuating rod 79 to the lower end of an operating crank 80 located at the rear end of a cross shaft 81 positioned above the lower end of the under conveyer 29. The shaft 81 is provided with extending fingers 82 which are normally positioned so that they are struck by the sheaves passing from the deck to the conveyer, with the result that each time a sheaf is ejected from the deck the shaft is turned and the crank operates to swing the bail bar and draw the pawl 76 back one tooth displacement on the ratchet wheel 75.

A spring 83 co-acting with the crank 80 is provided to reset the fingers 82 after a sheaf has passed and operates further to effect, in this resetting action, a pull in the rod 79 and the turning of the ratchet wheel in a counter clockwise direction one tooth displacement. The pawl 77, obviously, acts to prevent the ratchet wheel from turning during the interval that the pawl 76 is being thrown back to catch the next tooth.

From the above disclosure it will be apparent that as the sheaves pass to the elevator the counting mechanism will be actuated

one tooth displacement for each sheaf and 65 this movement winds up the cable an amount sufficient to turn the hand each time one division on the indicator. However, it is desirable that each time the basket is dumped the indicator be reset at the zero 70 mark, and to this end I provide an action actuated by the binder and controlling the pawls, which effects the release of the pawls from the ratchet wheel the instant the basket starts to dump. This action comprises, (see 75 Fig. 3) a rod 84 rotatably mounted on the underside of the beam 1' of the shocker frame, which rod is fitted at one end with a striker 85 and at the other with a crank 86, the striker being turned inwardly toward 80 the basket so that it will be engaged by the member 62 hereinbefore referred to.

The crank 86 is connected by means of a rod 87 to a controlling lever 88 pivotally secured at 89 to the side of the elevator. The 85 lever is supplied with a pair of flanges 90 and 91 which normally bear lightly against the free ends of the pawls and are arranged such that when the lever is swung by the rod 87 in a counter clockwise direction the 90 pawls are both simultaneously disengaged from the ratchet wheel. The turning of the said lever in the direction aforesaid is effected by the striker plate 62 hitting the striker 85 and effecting an up-push of the 95 rod 87 sufficient to swing the lever to disengage the pawls. The instant the pawls are disengaged the ratchet wheel is free and accordingly the hand 65 will be instantly thrown back to the zero position by the 100 action of the spring 68. In this connection it is pointed out that this movement occurs very quickly as the ratchet wheel is only released a very short interval owing to the fact that it only takes the plate 62 a very 105 short time to strike and pass the trip 85. Further, this action has to be quick for the reason that the counting mechanism has to be in the set or counting position before a sheaf can pass as all sheaves ejected 110 actuate it.

While I have described this indicator and the mechanism for operating it in detail, it will be readily understood that various parts can be readily modified without in the least 115 parting from the spirit of the invention, and as covered under the scope of the appended claims.

What I claim as my invention is:—

1. The combination with a shocking machine frame, an open topped sheaf receiving and shock forming basket pivotally secured to the frame, means for dumping the basket to one side of the frame and with the upper 120 end thereof overhanging the basket, of a hopper suspended between the elevator and the basket and adapted to receive the sheaves 125

elevated by the elevator and deliver them into the basket and means actuated by the basket adapted to close the hopper and prevent the delivery of sheaves to the basket 5 during the dumping operation.

2. The combination with a shocking machine frame, an open topped sheaf receiving and shock forming basket pivotally secured to the frame, means for dumping the basket 10 to deposit the shock and an elevator located to one side of the frame and with the upper end thereof overhanging the basket, of an open bottomed hopper suspended between the elevator and the basket and adapted to 15 receive the sheaves elevated by the elevator and deliver them into the basket, a pair of normally open pivoted gates attached to the bottom of the hopper and means actuated by the movement of the basket in the dumping 20 thereof for closing the gates during the interval that the basket is dumping to prevent the passage of the sheaves from the hopper.

3. In a shocking machine wherein the sheaves are delivered to a sheaf receiving 25 and shock forming basket, mechanical means for counting and visibly indicating by successive characters the successive sheaves delivered to the basket, said mechanical means being operated by the sheaves to effect the 30 counting and constructed so that it automatically becomes reset at zero the instant the basket commences to dump.

4. In combination with a shocking machine wherein the sheaves are delivered to a 35 sheaf receiving and shock forming basket, an indicator for indicating the number of sheaves and a counting mechanism connected with the indicator and arranged to be actuated by a sheaf in passage to the basket 40 whereby the number of sheaves delivered to the basket is automatically recorded by the counting mechanism actuating the indicator.

5. The combination with a shocking machine embodying a sheaf receiving and shock 45 forming basket, means for dumping the basket and an elevator for delivering the sheaves to the basket, of a suitably mounted indicator, a counting mechanism associated with the elevator and arranged to be actuated by each sheaf delivered to the basket 50 by way of the elevator, a connection between the counting mechanism and the indicator whereby the counting mechanism actuates the indicator to visibly indicate the total 55 number of sheaves delivered to the basket and means actuated by the basket in dump-

ing to effect the resetting of the indicator to zero.

6. The combination with a shocking machine embodying a sheaf receiving and shock forming basket, means for dumping the basket and an elevator for delivering the sheaves to the basket, of a suitably mounted indicator comprising a pointer operating over a scale presenting a zero mark, a return 60 spring and stop pin coacting to hold the pointer at the zero mark, a counting mechanism associated with the elevator and operated by the passing sheaves and a connection between the counting mechanism and the indicator effecting the movement of the indicator against the action of the spring to visibly indicate the number of sheaves passed to the basket and means for releasing the counting mechanism to permit the pointer to 65 return to the zero mark under the action of the spring.

7. The combination with a shocker frame, a sheaf receiving and shock forming basket carried by the frame, an elevator for receiving and delivering the sheaves to the basket and means for dumping the basket and returning the same to the initial sheaf receiving position, of an indicator mounted on the shocker frame and comprising a finger operating over a graduated scale presenting a zero mark and a spring and stop pin coacting to normally maintain the finger at the zero mark, a counting mechanism secured to the elevator, a cross shaft located at the receiving end of the elevator and provided with extending fingers adapted to be engaged by the successive sheaves passed to the elevator, a connection between the cross shaft and the counting mechanism effecting 90 the operation of the counting mechanism, a connection between the counting mechanism and the indicator whereby in the movement of the counting mechanism a hand visibly indicates on the scale the number of sheaves 95 passed to the basket by way of the elevator and means for releasing the counting mechanism to allow the hand to reset at zero mark and under the action of the spring each time the basket is dumped.

Signed at Winnipeg, this 19th day of March, 1918.

WILLIAM HACKLY CHURCH.

In the presence of—

G. S. ROXBURGH,
K. B. WAKEFIELD.
